(57) **CLAIM**

The ornamental design for a cryptocurrency seed bank, as shown and described.

DESCRIPTION

FIG. 1 is a front perspective view of a first plate of a cryptocurrency seed bank;

FIG. 2 is a back perspective view thereof;

FIG. 3 is a front elevation view thereof;

FIG. 4 is a back elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a back elevation view showing a second plate of a cryptocurrency seed bank;

FIG. 10 is a front elevation view thereof;

FIG. 11 is a back elevation view showing a third plate of a cryptocurrency seed bank;

FIG. 12 is a front elevation view thereof;

FIG. 13 is a front perspective view of a cryptocurrency seed bank showing the three plates combined;

FIG. 14 is a back perspective view thereof;

FIG. 15 is a top plan view thereof;

FIG. 16 is a front exploded view thereof;

FIG. 17 is a back exploded view thereof; and,

FIG. 18 is a top exploded view thereof.

The evenly spaced broken lines in the drawings depict portions of the cryptocurrency seed bank that form no part of the claimed design.

1 Claim, 8 Drawing Sheets
